G. O. DEGENER & J. E. DAVIDSON.
COMBINED TYPE WRITING AND COMPUTING MACHINE.
APPLICATION FILED NOV. 21, 1912.

1,163,644.

Patented Dec. 14, 1915.

UNITED STATES PATENT OFFICE.

GUSTAVE O. DEGENER AND JOSHUA E. DAVIDSON, OF NEW YORK, N. Y., ASSIGNEES TO
UNDERWOOD COMPUTING MACHINE COMPANY, OF NEW YORK, N. Y., A CORPORA-
TION OF NEW YORK.

COMBINED TYPE-WRITING AND COMPUTING MACHINE.

1,163,644.

Specification of Letters Patent. Patented Dec. 14, 1915.

Application filed November 21, 1912. Serial No. 732,626.

To all whom it may concern:

Be it known that we, GUSTAVE O. DEGENER and JOSHUA E. DAVIDSON, residing in the city, county, and State of New York, both citizens of the United States, have invented certain new and useful Improvements in Combined Type-Writing and Computing Machines, of which the following is a specification.

10 This invention relates to combined typewriting and computing machines, and is herein illustrated as applied to a combined typewriting and computing machine of the Underwood-Wright type in which the numeral keys of the typewriter cause computing wheels to be engaged *seriatim* by a master wheel and to be turned thereby to an extent determined by the numeral keys of the typewriter. The computing wheels are 15 grouped in a gang or gangs which form portions of totalizers, and said totalizers are arranged to be adjustably mounted on a totalizer carriage, which carriage moves step-by-step with the typewriter carriage 20 and is adjustably connected thereto. Said totalizer carriage may comprise a channeled bar having a flat upper surface on which the frames of the totalizers may rest. Each totalizer may comprise a bib or extension, which has a tongue arranged to enter 25 said channel to steady the totalizers. On the bib may be mounted a locking member arranged to enter openings in said channeled bar and catch back of said openings, 30 these openings being spaced at definite intervals or distances apart, which bear a definite, predetermined relation to the wheels or computing members of the totalizers, so that the positions of the openings correspond to those of the aforesaid computing members. Said lock may comprise a cam 35 for positively drawing the bib of the totalizer against said channeled bar, so as to hold the totalizer positively in place. The 40 totalizer carriage may also comprise a rack bar which has stops set on it, and a bar pivoted on the typewriter carriage may be arranged to engage any of said stops at will and thus couple the two carriages together 45 and cause them to travel in unison.

50 Other features and advantages will hereinafter appear.

In the accompanying drawings, Figure 1 represents so much of the front of an Un-

derwood-Wright combined typewriting and adding machine as is sufficient for the understanding of our invention. Fig. 2 is a perspective view of a totalizer and the channeled bar to which it is fastened. Fig. 3 is an enlarged view of a locking member omitting the bib of the totalizer. Figs. 4 and 5 are sections through the locking member in different positions. Figs. 6 and 7 are front views of the same.

The numeral keys (not shown) of the typewriter by any preferred mechanism, cause a shaft 1 to be rotated to an extent determined by the numeral key operated. The type keys (not shown), including said numeral keys, also cause the carriage of the typewriter (not shown herein) to feed forward in letter-feeding direction. The shaft 1, controlled in its turning by the numeral keys, through a clutch 2 causes a master wheel shaft 3 to rotate either backwardly or forwardly, so that a master wheel 4 thereon may turn the dial or computing wheel 44 within the totalizer 5 with which the master wheel engages. Said master wheel shaft is journaled in the frame at the right hand of the machine, and adjacent the master wheel, it extends into a sleeve 6 of an arbor 7; said arbor extending to the left hand side of the machine where it enters an upright 8 on the frame and is held thereon in position by means of a pin 9 against which the end of the arbor bears, said pin being retained in position by means of a spring 10 fastened to said upright 8 by a screw 11. By removing the pin 9, it will be seen that the arbor 7 can be withdrawn from within any totalizer through which it may be extending, forming as it does the extension of the master wheel shaft, whereupon such totalizer may readily be removed from the machine.

The totalizers 5, of which there are four shown in Fig. 1, the right hand one being broken away, comprise casings 12 having flat bottoms 13, which rest on the flat upper surface 14 of a channeled bar 15. Each totalizer comprises an extension 16 in the form of a bib which overlaps the front of the channeled bar. Each bib has thereon a tongue 17 which enters within said channeled bar and bears against a wall 18 formed as a bar rabbeted into both the upper and the lower members of said channeled bar. Said bar 18 is provided with openings 19 which

are vertically elongated and rounded at their ends, and are arranged to allow a T-shaped locking member 20 to pass therethrough, and then to be turned transversely so that its head 21 then bears against the inner surface of the bar 18. Each locking member 20 includes the transverse T-head 21 and the stem 22, which stem has pivoted thereon at its outer end a handle 23 comprising a locking cam face 24 arranged, when the handle is turned in one direction parallel to the face of the locking bar, to bear against the bib 16 and so draw the T-head 21 forward against the internal face of the bar 18 and so positively lock the bib to said bar. The cam 24 does not bear directly on the bib 16, but against a circular plate 25 sunk in a depression of said bib and having a tongue 26 extending across a kerf in the stem 22, against which kerf the cam 24 is arranged to bear, as seen in Fig. 3. For the purpose of bearing in this manner, the handle 23 is pivoted so that it lies and swings within said kerf.

25 In locking the locking member 20, by means of the cam 24, the plate 25 is moved against the tension of a cone spring 27 lying within a pocket in the bib 16 surrounding the locking member 20. The plate 25 has 30 cut from its periphery a segment 28, and through the segment projects a pin 29 arranged to strike the ends of said segment whenever the handle rotates the locking member and the plate to one side or the other, and thus said pin limits the amount 35 of throw of said handle sidewise. Said segment has its ends so cut that when one end is in contact with the pin 29, the T-head 21 of the locking member 20 will pass freely 40 through the opening 19, while if the other end of said segment is in contact with said pin 29, the T-head lies squarely across the opening 19. The spring 27, it will be observed, positively loosens the parts whenever 45 the handle 23 is swung to releasing position. The sides of the tongue 17, it will be noted, lie close against the upper and lower members of the channeled bar 15, and thus coöperate with the bottom 13 of the totalizer 50 in alining it.

The channeled bar 15 forms part of a totalizer carriage which also comprises a top bar 30 and ends 31 and 32 and slides on upper and lower guide rails 37 and 38 fast in 55 brackets at the ends of the typewriter frame. Said top bar 30 is adjustable between said ends 31 and 32, which ends are fast to the channeled bar 15, and said bar 30 comprises a rack 33 on which stops 34 can be set at letter-space intervals corresponding to the pitch of the letter-feed of the typewriter. The totalizer carriage is adapted to be driven by said stops 34 by means of an arm 35, pivoted at 36 on the typewriter carriage, 60 so as to travel therewith.

It will be noted that by means of the openings 19, the various totalizers can be separately adjusted on the totalizer carriage, and that by means of the stops 34 and the rack 33, the totalizer carriage can be adjusted as a whole relatively to the typewriter carriage. In this connection, it may be stated that there is a definite correspondence between the arrangement of the openings 19 and the computing wheels 44, or, in other words, a predetermined relation between the spaces or intervals at which the openings are arranged, and the positions of the computing wheels 44. This is a matter of extreme importance, for the reason that inasmuch as the master wheel moves successively from one computing wheel to the one of next higher order, such movement must be preserved for all positions of the totalizer, so as to insure proper actuation of the computing wheels by the master wheel. Furthermore, since the openings 19 are located at regular intervals, the bar 15 wherein they are formed constitutes, in effect, a rack, in the broad meaning of that term, as will be understood. It will also be seen that the locking members 20 are journaled in openings 40 in the bib 16 and so are held each in its bib by means of the T-heads 21. There are, therefore, no parts that would become detached whenever a totalizer is removed from the machine, and the locking member 20 always remains attached to its own totalizer.

Variations may be resorted to within the scope of the invention, and portions of the improvements may be used without others.

Having thus described our invention, we claim:

1. A clamping mechanism for the totalizer of a combined typewriting and computing machine, comprising, in combination, a bar whereon the totalizer is mounted for bodily adjustment and detachment, said bar being provided with elongated openings spaced at definite intervals corresponding to the intervals of the computing members of the totalizer, an extension on said totalizer lying against the face of said bar, and a latch comprising an elongated head arranged to be inserted interchangeably through any one of said openings when attaching the totalizer, to exactly locate said totalizer on said bar, and to be turned to lock it to the same, said head being withdrawable from said opening when detaching the totalizer.

2. A clamping mechanism for the totalizer of a combined typewriting and computing machine, comprising, in combination, a bar whereon the totalizer is mounted for bodily adjustment and detachment, said bar being provided with elongated openings spaced at definite intervals corresponding to the intervals of the computing members of the totalizer.

izer, an extension on said totalizer lying against the face of said bar, a latch on said extension, an abutment on said latch arranged to be inserted interchangeably through any one of said openings when attaching the totalizer, to exactly locate said totalizer on said bar, and to be turned transversely to the opening to lock said totalizer to said bar, and a spring drawing said abutment against said bar, said abutment being withdrawable from said opening when detaching the totalizer.

3. A clamping mechanism for the totalizer of a combined typewriting and computing machine, comprising, in combination, a bar whereon the totalizer is mounted for bodily adjustment and detachment, said bar being provided with elongated openings spaced at definite intervals corresponding to the intervals of the computing members of the totalizer, an extension on said totalizer lying against the face of said bar, a rotatable latch on said extension comprising an abutment arranged to be inserted interchangeably through any one of said openings when attaching the totalizer, to exactly locate said totalizer on said bar, and to be turned to lock it to the same, and a cam on said latch arranged to be turned to draw said abutment to bear tight against said bar, said abutment being withdrawable from said opening when detaching the totalizer.

4. A clamping mechanism for the totalizer of a combined typewriting and computing machine, comprising, in combination, a bar whereon the totalizer is mounted for bodily adjustment and detachment provided with elongated openings spaced at definite intervals corresponding to the intervals of the computing members of the totalizer, an extension on said totalizer lying against the face of said bar, a rotatable latch on said extension, an abutment on said latch arranged to be inserted interchangeably through any one of said openings when attaching the totalizer, to exactly locate said totalizer on said bar, and to be turned to lock said totalizer to said bar, a plate fast on said latch to limit its rotation, and a cam rotatable on said latch to bear against said plate to draw said abutment against said bar thereby locking said extension to said bar, said abutment being withdrawable from said opening when detaching the totalizer.

5. A clamping mechanism for the totalizer of a combined typewriting and computing machine, comprising, in combination, a channeled bar whereon the totalizer is mounted for bodily adjustment and detachment, said bar being provided with openings or spaces having a definite arrangement corresponding to the arrangement of the computing members of the totalizer, an extension on said totalizer comprising a tongue fitting within said channel, and a lock on said ex-

tension arranged to interchangeably engage any one of the said spaces when attaching said totalizer, to exactly locate the totalizer on said bar and to lock it to the same by drawing said tongue against said bar, said lock being releasable from said space when detaching said totalizer.

6. A clamping mechanism for the totalizer of a combined typewriting and computing machine, comprising, in combination a channeled bar whereon the totalizer is mounted for bodily adjustment and detachment, an extension on said totalizer comprising a tongue fitting within said channel, the bottom of the channel being provided with elongated openings spaced at definite intervals corresponding to the intervals of the computing members of the totalizer, a latch comprising an abutment arranged to be inserted interchangeably through any one of said openings when attaching the totalizer, to exactly locate said totalizer on said bar, and to be turned to lock it to the same, and a cam for drawing said abutment against said bar, said abutment being withdrawable from said opening when detaching the totalizer.

7. A clamping mechanism for the totalizer of a combined typewriting and computing machine, comprising, in combination, a bar whereon said totalizer is mounted for bodily adjustment and detachment, said bar having a channeled face and openings or spaces which have a definite arrangement corresponding to the arrangement of the computing members of the totalizer, a tongue on said totalizer arranged to fit within said channel, and a lock arranged to interchangeably engage any one of said spaces when attaching said totalizer, to exactly locate the totalizer on said bar and to lock it to the same, said lock being releasable from said space when detaching said totalizer.

8. A clamping mechanism for the totalizer of a combined typewriting and computing machine, comprising, in combination, a bar whereon the totalizer is mounted for bodily adjustment and detachment, said bar having a channeled face, the bottom of which is formed with openings spaced at definite intervals corresponding to the intervals of the computing members of the totalizer, a tongue on said totalizer arranged to fit within said channel, a member comprising an abutment arranged to be inserted interchangeably through any one of said openings when attaching the totalizer, to exactly locate said totalizer on said bar and to lock it to the same, and means for locking said abutment against said bar, said abutment being withdrawable from said opening when detaching the totalizer.

9. A clamping mechanism for the totalizer of a combined typewriting and computing machine, comprising, in combination, a

- bar whereon the totalizer is mounted for bodily adjustment and detachment, said bar having openings or spaces which have a definite arrangement corresponding to the 5 arrangement of the computing members of the totalizer, an extension on said totalizer arranged to lie against said bar, a lock on said extension arranged to interchangeably engage any one of said spaces when attaching 10 said totalizer, to exactly locate the totalizer on said bar and to rigidly secure it thereto, and a cam for locking said lock, said lock being releasable from said space when detaching said totalizer.
- 15 10. A clamping mechanism for the totalizer of a combined typewriting and computing machine, comprising, in combination, a bar whereon the totalizer is mounted for bodily adjustment and detachment, said bar 20 having a longitudinal series of elongated openings spaced at definite intervals corresponding to the intervals of the computing members of the totalizer, and a locking member having a T-head arranged to pass 25 interchangeably through any one of said openings and to lock therewith when attaching the totalizer, to exactly position said totalizer on said bar and rigidly secure it to the same, said head being withdrawable 30 from said opening when detaching the totalizer.
11. In a clamping mechanism for the totalizer of a combined typewriting and computing machine embodying a carriage, the combination of a bar whereon the totalizer is mounted for bodily adjustment and detachment, said bar having a channeled face provided with openings or spaces which have a definite arrangement corresponding 35 to the arrangement of the computing members of the totalizer, a tongue on said totalizer fitting within the channel in said face, and means on said tongue arranged to interchangeably engage any one of said spaces when attaching 40 said totalizer, to exactly locate the latter on said bar and to rigidly secure it to the same, said means being releasable from said space when detaching said totalizer.
- 45 12. In a clamping mechanism for the totalizer of a computing machine embodying a carriage, the combination of a bar whereon the totalizer is mounted for bodily adjustment and detachment forming part of said carriage, said bar having one face provided with elongated openings having a definite arrangement corresponding to the arrangement of the computing members of the totalizer, a bib attached to said totalizer and 55 lying against the said face of said bar, and a locking device comprising an elongated head arranged to be inserted interchangeably through any one of said openings when attaching said totalizer, to exactly locate the latter on said bar, and to be turned to rig- 60 idly secure it to said bar, said head being withdrawable from said opening when detaching the totalizer.
13. In a clamping mechanism for the totalizer of a computing machine embodying a carriage, the combination of a bar whereon the totalizer is mounted for bodily adjustment and detachment forming part of said carriage, said bar having one face provided with elongated openings having a 70 definite arrangement corresponding to the arrangement of the computing members of the totalizer, a bib attached to said totalizer and lying against the said face of said bar, a handle on said bib, a lug on said handle arranged to be interchangeably inserted through any one of said openings when attaching said totalizer, to exactly locate the latter on said bar, and to be turned transversely to said opening to catch and rigidly 75 secure said totalizer to said bar, and a spring drawing said lug against said bar, said lug being withdrawable from said opening when detaching the totalizer.
14. In a clamping mechanism for the totalizer of a computing machine embodying a carriage, the combination of a bar whereon the totalizer is mounted for bodily adjustment and detachment forming part of said carriage, one face of said bar being provided with elongated openings having a 80 definite arrangement corresponding to the arrangement of the computing members of the totalizer, a bib attached to said totalizer and lying against the said face of said bar, a 85 rotatable latch journaled in said bib and comprising a lug arranged to be interchangeably inserted through any one of said openings when attaching said totalizer, to exactly locate the latter on said bar, and to be turned to lock said totalizer to said bar, and a handle on said latch having a cam arranged to be turned to draw said lug 90 tight against said bar, said lug being withdrawable from said opening when detaching the totalizer.
15. In a clamping mechanism for the totalizer of a computing machine embodying a carriage, the combination of a bar whereon the totalizer is mounted for bodily adjustment and detachment forming part of said carriage, one face of said bar being provided with elongated openings having a 95 definite arrangement corresponding to the arrangement of the computing members of the totalizer, a bib connected to said totalizer and lying against the said face of said bar, a latch rotatably journaled in said bib, a lug on said latch arranged to be interchangeably inserted through any one of said 100 openings when attaching said totalizer, to exactly locate the latter on said bar, and to be turned to lock said bib to said bar, a plate fast on said latch to limit its rotation, and a rotatable handle on said latch having a 105
- 110
- 115
- 120
- 125
- 130

- cam to bear against said plate, to draw said lug tight against said bar, said lug being withdrawable from said opening when detaching the totalizer.
- 5 16. In a clamping mechanism for the totalizer of a computing machine, the combination of a bar whereon the totalizer is mounted for bodily adjustment and detachment, said bar having a channeled face and openings or spaces which are arranged at definite intervals corresponding to the intervals of the computing members of the totalizer, an extension on said totalizer having a tongue fitting in the channel in said face, 10 and a lock on said extension passing through said tongue and arranged to interchangeably engage any one of said spaces when attaching the totalizer, to exactly locate said totalizer on said bar and rigidly secure it 15 to the same by drawing said tongue into said channel, said lock being releasable from said space when detaching said totalizer.
17. In a clamping mechanism for the totalizer of a computing machine, the combination of a bar whereon the totalizer is mounted for bodily adjustment and detachment, one face of said bar being provided with a longitudinal series of openings having a definite arrangement corresponding to 20 the arrangement of the computing members of the totalizer, a rotatable lock journaled on said totalizer and arranged to be inserted interchangeably into any one of said openings when attaching the totalizer, 25 to exactly locate said totalizer on said bar and rigidly secure it to the same, and means for limiting the rotation of said lock in both directions, said lock being withdrawable from said opening when detaching said 30 totalizer.
18. In a clamping mechanism for the totalizer of a computing machine, the combination of a bar whereon the totalizer is mounted for bodily adjustment and detachment, one face of said bar being provided with a longitudinal series of openings having a definite arrangement corresponding to 35 the arrangement of the computing members of the totalizer, a rotatable lock journaled on said totalizer and arranged to be inserted interchangeably into any one of said openings when attaching the totalizer, 40 to exactly locate said totalizer on said bar and rigidly secure it to the same, a pin on said extension, and a member fast on said lock and having a notch coöperating with said pin for limiting the rotation of said lock in both directions, said lock being withdrawable from said opening when detaching said 45 totalizer.
19. In a clamping mechanism for the totalizer of a computing machine, the combination of a bar whereon the totalizer is mounted for bodily adjustment and detachment, one face of said bar being provided with a longitudinal series of openings having a definite arrangement corresponding to the arrangement of the computing members of the totalizer, a rotatable lock journaled on said totalizer and arranged to be inserted interchangeably into one of said 50 openings when attaching the totalizer, to exactly locate said totalizer on said bar and rigidly secure it to the same, a pin on said totalizer, and a member fast on said lock and having a notch coöperating with said 55 pin for limiting the rotation of said lock in both directions, said lock being withdrawable from said opening when detaching said totalizer.
20. In a clamping mechanism for the totalizer of a computing machine, the combination of a bar whereon the totalizer is mounted for bodily adjustment and detachment, one face of said bar being provided with openings or spaces which have a definite arrangement corresponding to the arrangement of the computing members of the totalizer, an extension on the totalizer arranged to lie against said bar, a rotatable lock journaled on said extension and arranged to interchangeably engage any one of said spaces when attaching the totalizer, 60 to exactly locate the latter on said bar and rigidly secure it to the same, a pin on said extension, and a member fast on said lock and having a notch coöperating with said pin to limit the rotation of the lock in both directions, said lock being releasable from 65 said space when detaching said totalizer.
